DESIGN FOR A CARPET SWEEPER

Thomas M. Mock and Harold H. Weber,
Beverly Hills, Calif.

Application January 17, 1949, Serial No. 267

Term of patent 14 years

(Cl. D9—2)

To all whom it may concern:

Be it known that we, Thomas M. Mock and Harold H. Weber, both citizens of the United States, and residents of the city of Beverly Hills, in the county of Los Angeles and State of California, have invented a new, original, and ornamental Design for a Carpet Sweeper, of which the following is a specification, reference being had to the accompanying drawings, forming part thereof, in which:

Fig. 1 is a perspective view of a carpet sweeper, showing our new design;

Fig. 2 is a plan view;

Fig. 3 is a side view thereof, the handle fragmented for convenience of illustration, and

Fig. 4 is an end view thereof, the handle fragmented for convenience of illustration.

We claim:

The ornamental design for a carpet sweeper, as shown.

THOMAS M. MOCK.
HAROLD H. WEBER.
